Primary Examiner — Derrick E Holland(74) *Attorney, Agent, or Firm* — Martin Fessenmaier;
Umberg Zipser LLP(57) **CLAIM**

I claim the ornamental design for a rotor assembly for a generator, as shown and described.

DESCRIPTION

FIG. 1 is a perspective view of a rotor assembly for a generator.

FIG. 2 a top plan view of the rotor assembly for a generator.

FIG. 3 is a bottom plan view of the rotor assembly for a generator.

FIG. 4 is a front elevation view of the rotor assembly for a generator.

FIG. 5 is a back elevation view of the rotor assembly for a generator.

FIG. 6 is a left side elevation view of the rotor assembly for a generator.

FIG. 7 is a right side elevation view of the rotor assembly for a generator; and,

FIG. 8 is a top plan view of the rotor assembly for a generator with one endplate removed illustrating placement of magnets (in broken lines) in the rotor assembly.

The broken lines shown depict the portions of the rotor assembly for a generator that form no part of the claimed design.
